5 Claims. (Cl. 230—175)

The present invention relates to a compressor unit for refrigeration and other applications, and the principal object of the invention is to provide novel and advantageous devices of the general character specified.

An important feature of the invention relates to the provision of a compressor unit in which the working parts may be arranged in very compact form in a closed casing. Another important 10 feature relates to the provision of a simple and economical construction whereby upkeep is rendered substantially negligible.

In carrying out the invention in a preferred way, the apparatus comprises driving means, 15 preferably an electric motor, and one or more compressing devices. Although a single cylinder compressor device may be used, preferably these devices comprise one or more groups of two cylinders diametrically opposed with reference 20 to a shaft coaxial with the rotor of the motor and the shaft is utilized to operate a double piston for each pair of opposed cylinders. Preferably the driving connection between the shaft and the double piston is effected by means of an 25 eccentric on the shaft and fitting in a collar fixed to the double piston. In view of this connection provision should be made for sidewise movement of the double-cylinder assembly. This requirement may be met by mounting the double-cylinder assembly to turn about a pivot parallel to the axis of the shaft. The inlet of the 30 casing is in alignment with the pivot for the double cylinders and the connections from the inlet to the cylinders swings with the cylinders.

All of the working parts of the compressor unit may be housed in a gas-tight casing into which the compressed refrigerant is discharged from the compressor cylinders. The lubricant for the working parts may be placed in the casing and distributed by a splash system operating 40 with the aid of the compressed gas discharged from the cylinders and passing through the lubricant, thereby atomizing the liquid and driving it to the desired locations, the oil being prevented by a filter from passing out of the casing with the compressed refrigerant. Thorough lubrication may be aided by providing suitable lubrication ducts in certain of the parts.

Other objects, features and advantages will 50 appear upon consideration of the following detailed description and of the drawings, in which—

Fig. 1 is an axial section of a compressor unit constituting a preferred embodiment of the invention; and

Fig. 2 is a section on the line 2—2 of Fig. 1.

Referring to the drawings, the compressor unit may comprise an electric driving motor 10, the rotor 11 of which is keyed to a shaft 12 on which is provided an eccentric 13 embraced by a collar 14 integral with two pistons 15 and 16 at opposite sides thereof. These pistons are located respectively in two cylinders 17 and 18 diametrically opposed relative to shaft 12 and joined by a frame 19 so as to form an entirely rigid compressor pump unit. This rigid unit may be mounted to swing about a vertical fulcrum or pivot 20 mounted in a casing member 21 closed at the bottom by a member 22 and housing in its upper- 10 part the electric motor 10.

Shaft 12 is mounted in bearings 24, 25 provided in casing member 21 and bottom member 22 and the lower end of said shaft rests on a ball 26 at the bottom of the lower bearing 25.

In cylinders 17 and 18, are provided inlet ports 27 and 28 opening into chambers 29 and 30, respectively, joined by a duct 31 communicating with a conduit 32 coaxial with the fulcrum pin 20 of the unit comprising cylinders 17 and 18. This conduit 32 communicates through a suitable expansion joint 33 with a check valve fitting 34 connected to an intake pipe (not shown) supplying refrigerant from the system. The said expansion joint may comprise a resilient metal bellows or sylphon 35 enclosed in a compression spring 36.

The bottoms 37 and 38 of cylinders 17 and 18 are provided with outlet valves 39 and 40 which discharge into the casing. Connected with the top of the casing is a feed line 41 leading to the evaporator of the refrigeration plant (not shown).

For lubrication purposes, the lower part of the casing may be filled with liquid lubricant which may be distributed by the splash method carried out partly by the moving parts and to a greater extent by the compressed refrigerant discharged from the ends of the cylinders 17 and 18. The lubricant will be atomized to a considerable extent and thrown to all parts at 45 the interior of the casing, passage of the lubricant or oil from the casing being prevented by suitable means such as a filter 42 over the end of the feed line 41. Lubrication may also be facilitated by providing suitable ducts and channels in different parts.

By mounting the cylinder structure to oscillate about the pivot 20, it is made possible to drive the pistons 15 and 16 directly from the shaft 12 by means of the eccentric 13 and collar 55

14. The stroke of the pistons is short and the oscillatory movement of the piston is of small amplitude as indicated in the dot-and-dash lines of Fig. 2. To assist in balancing the unit use 5 may be made of a weight 43 carried by the shaft 12.

Preferably the cylinders 17 and 18 and the hollow pistons 15 and 16 are open at their inner 10 ends so as to permit the compressed refrigerant in the casing to enter the pistons and substantially balance the pressure at the other side of the piston in its compression stroke.

Assuming the parts in the positions shown in Fig. 1, rotation of the eccentric 13 by the motor 15 will cause movement of the pistons 15 and 16 to the left. As soon as the port 27 is closed by the piston 15, the piston acts to force refrigerant in the cylinder 17 out of the outer end of the cylinder against the pressure in the casing, the outlet 20 check valve remaining closed until the pressure in the cylinder is greater than that in the casing. The simultaneous movement of piston 16 to the left will cause valve 40 to remain closed and a vacuum will be produced in cylinder 18. As soon, 25 however, as the piston 16 uncovers the port 28, the low pressure refrigerant will be drawn into the cylinder. Upon reversal of the movement of the pistons, the piston 15 will act to draw low pressure refrigerant into cylinder 17 and piston 30 16 will act to force refrigerant under high pressure into the interior of the casing which provides a reservoir for the high pressure refrigerant. These actions may of course be repeated as many times as required. During the operation 35 the oil or lubricant in the casing will be splashed around and also atomized by the compressed refrigerant expelled from the cylinders 17 and 18.

Any desired number of pumping devices such 40 as those constituted by cylinders 17 and 18 may be mounted along shaft 12, these pumping devices being preferably evenly spaced along the shaft, either on one side only of rotor 11 or on both sides thereof, the eccentrics, which drive the 45 corresponding pistons, being suitably arranged to obtain complete equilibrium of the unit.

Shaft 12 can be mounted in any desired position, either vertically as shown in the drawings or horizontally or in any desired inclination.

50 The invention is applicable to the compression of volatile fluids in refrigeration machines of all kinds and for all purposes, and more particularly for domestic installations, due to the small dimensions of the compressor group made possible by 55 the present invention.

An important feature of the invention relates to the arrangement of the cylinders on opposite sides of the shaft thus enabling the compressor unit to be made relatively flat.

60 It should be understood that various changes may be made in the construction and arrangement of parts and that various features may be used without others without departing from the true scope and spirit of the invention.

65 Having thus described my invention, I claim:

1. In a device of the character described, a housing having an inlet and an outlet, a shaft mounted in said housing, means for driving said shaft, an eccentric on said shaft, a collar fitting 70 over said eccentric, aligned pistons connected to said collar at diametrically opposite points,

aligned cylinders receiving said pistons and connected with each other to form a rigid assembly, outlets for said cylinders discharging into said housing which serves as a receiver for compressed liquid, inlets for said cylinders connected with the inlet for said housing, and means connecting said cylinders with said housing whereby a sidewise movement is imparted to said cylinders during the reciprocation of said pistons.

2. In a device of the character described, a 10 housing having an inlet and an outlet, a shaft mounted in said housing, a motor in said housing and having its rotor mounted on said shaft to drive the same, a cylindrical member eccentrically mounted on said shaft, a collar surrounding said 15 cylindrical member, aligned pistons rigidly attached to said collar at diametrically opposite sides thereof, aligned cylinders receiving said pistons and rigidly connected with each other, outlets at the outer ends of said cylinders discharging into said housing which serves as a receiver for the compressed fluid, inlets to admit fluid to said cylinders, means connecting said cylinders with said housing whereby a sidewise movement is imparted to said cylinders during 20 the reciprocation of said pistons, and flexible connections between the inlet for said housing and the inlets of said cylinders.

3. In apparatus of the class described, a housing having an inlet and an outlet, a shaft 30 mounted in said housing, a motor having its rotor on said shaft to rotate the same, an eccentric on said shaft, a collar on said eccentric, aligned pistons rigidly connected with said collar at opposite sides thereof, aligned cylinders receiving said pistons and rigidly connected with each other to form a frame, outlets for said cylinders discharging into said housing which serves as a receiver for compressed liquid, inlets for said cylinders connected with the inlet for said housing, and a pivot for one end portion of said frame mounted in said casing whereby the cylinders will 40 oscillate during the reciprocation of the pistons.

4. In apparatus of the class described, a relatively flat casing, a shaft extending from end to 45 end of said casing and journalled therein, a motor mounted in said casing and having a rotor on said shaft to drive the same, aligned cylinders on opposite sides of said shaft and having a rigid connection therebetween spaced from the shaft, 50 aligned pistons in said cylinders and having a rigid connection, a pivot eccentrically mounted on said shaft and fitting into a corresponding opening in said rigid connection between the pistons and acting on said pistons to reciprocate 55 the same and move them sidewise, and means connecting said casing with the cylinders to prevent longitudinal reciprocation of the cylinders while permitting sidewise movement.

5. In apparatus of the class described, a housing, a shaft mounted in said housing, a motor in said casing having a rotor on said shaft to rotate the same, cylinders at opposite sides of the shaft, pistons in said cylinders, shaft-operated eccentric means for reciprocating said pistons and 65 moving them sidewise, and connections between the housing and said cylinders to prevent axial reciprocation of said cylinders while permitting sidewise movement.
